(57) CLAIM

The ornamental design for a portable storage battery, as shown and described.

DESCRIPTION

FIG. 1 is a front elevational view of a portable storage battery showing a first embodiment;
FIG. 2 is a top plan view thereof;
FIG. 3 is a rear elevational view thereof;
FIG. 4 is a bottom plan view thereof;
FIG. 5 is a right side view thereof;
FIG. 6 is a left side view thereof;
FIG. 7 is a front elevational view of a portable storage battery showing a second embodiment;
FIG. 8 is a top plan view thereof;
FIG. 9 is a rear elevational view thereof;
FIG. 10 is a bottom plan view thereof;
FIG. 11 is a right side view thereof; and,
FIG. 12 is a left side view thereof.
